(57) **CLAIM**

The ornamental design for a breathing tube with mesh, as
shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a top, front, and side perspective view of a first
embodiment of a breathing tube with mesh showing a tubing
assembly embodying our new design.

FIG. 2 is a bottom view thereof.

FIG. 3 is a top view thereof.

FIG. 4 is a left side view thereof.

FIG. 5 is a right side view thereof.

FIG. 6 is a front view thereof.

FIG. 7 is a rear view thereof.

FIG. 8 is an enlarged view of a portion of FIG. 4, showing
a bead that is shaded for a contrasting color being positioned
between intervening portions of a wall of a conduit of the
breathing tube with mesh.

FIG. 9 is a top, front, and side perspective view of a second
embodiment of a breathing tube with mesh showing a tubing
assembly embodying our new design.

FIG. 10 is a bottom view thereof.

FIG. 11 is a top view thereof.

FIG. 12 is a left side view thereof.

FIG. 13 is a right side view thereof.

FIG. 14 is a front view thereof.

FIG. 15 is a rear view thereof.

FIG. 16 is an enlarged view of a portion of FIG. 13, showing
a bead that is shaded for a contrasting color being positioned
between intervening portions of a wall of a conduit of the
breathing tube with mesh.

FIG. 17 is a top, front, and side perspective view of a third
embodiment of a breathing tube with mesh showing a tubing
assembly embodying our new design.

FIG. 18 is a bottom view thereof.

FIG. 19 is a top view thereof.

FIG. 20 is a left side view thereof.

FIG. 21 is a right side view thereof.

FIG. 22 is a front view thereof.

FIG. 23 is a rear view thereof.

FIG. 24 is an enlarged view of a portion of FIG. 21, showing
a bead that is blue in color.

(Continued)

FIG. 25 is a top, front, and side perspective view of a fourth embodiment of a breathing tube with mesh showing a tubing assembly embodying our new design.

FIG. 26 is a bottom view thereof.

FIG. 27 is a top view thereof.

FIG. 28 is a left side view thereof.

FIG. 29 is a right side view thereof.

FIG. 30 is a front view thereof.

FIG. 31 is a rear view thereof; and,

FIG. 32 is an enlarged view of a portion of FIG. 29, showing a bead that is blue in color.

Broken lines are used to illustrate portions of the breathing tube with mesh that form no part of the claimed design. The break lines in the drawings illustrate a break in length and the area between form no part of the claimed design.
